US00D812075S

(12) **United States Design Patent** (10) **Patent No.:** **US D812,075 S**
(45) **Date of Patent:** **** Mar. 6, 2018**

(54) **BUILDING MONITORING DISPLAY WITH GRAPHICAL USER INTERFACE**

(71) Applicant: **Mitsubishi Electric Corporation**, Tokyo (JP)

(72) Inventor: **Hirofumi Fukagawa**, Tokyo (JP)

(73) Assignee: **Mitsubishi Electric Corporation**, Tokyo (JP)

(**) Term: **14 Years**

(21) Appl. No.: **29/525,446**

(22) Filed: **Apr. 29, 2015**

(30) **Foreign Application Priority Data**

Nov. 21, 2014 (JP) 2014-026108

(51) **LOC (11) Cl.** **14-04**

(52) **U.S. Cl.**

USPC **D14/486**; D14/493

(58) **Field of Classification Search**

(57) **CLAIM**

The ornamental design for a building monitoring display with graphical user interface, as shown and described.

DESCRIPTION

The FIGURE is a building monitoring display with graphical user interface, showing my new design. The evenly-spaced broken lines shown in the drawing illustrate portions of the building monitoring display with graphical user interface that form no part of the claimed design. The dash-dot lines illustrate the bounds of the claim and form no part of the claimed design.
